Japan[57] **CLAIM**[**] Term: **14 Years**

The ornamental design for a developing unit for an image forming apparatus, as shown and described.

[21] Appl. No.: **77,640****DESCRIPTION**[22] Filed: **Oct. 6, 1997**

FIG. 1 is a front view of the developing unit;

[30] **Foreign Application Priority Data**

FIG. 2 is a rear view of the developing unit;

Apr. 15, 1997 [JP] Japan 9-51513

FIG. 3 is a top view of the developing unit;

[51] **LOC (6) Cl.** **16-03**

FIG. 4 is a bottom view of the developing unit;

[52] **U.S. Cl.** **D18/40**

FIG. 5 is a left side view of the developing unit;

[58] **Field of Search** D18/36, 40, 43,

FIG. 6 is a right side view of the developing unit;

D18/56; 222/DIG. 1; 399/24, 25, 27, 31,
119, 130, 252, 262

FIG. 7 is a perspective view of the developing unit; and,

[56] **References Cited**

FIG. 8 is another perspective view of the developing unit.
